DESIGN FOR A WRIST WATCH STRAP BUCKLE

Charles B. Greenberg, New York, N. Y.

Application October 22, 1937, Serial No. 72,362

Term of patent 14 years

To all whom it may concern:

Be it known that I, Charles B. Greenberg, a citizen of the United States, residing at 8 Washington Place, in the county of New York, city and State of New York, have invented a new, original, and ornamental Design for Wrist Watch Strap Buckles, of which the following is a specification, reference being had to the accompanying drawing, forming part thereof.

Fig. 1 is a bottom perspective view of a wrist watch strap buckle showing my new design, and

Fig. 2 is a top perspective view thereof.

The characteristic features of my design reside in a buckle of the type shown, comprising a back terminating in side arms, said back being divided into a narrow horizontal portion and a relatively wide forward and downwardly extending apron having clipped off corners. The side arms have horizontal flat upper faces and vertical broad sides, the upper faces continuing the line of the narrow horizontal back portion and the broad sides extending downwardly to about the level of the lower part of the apron.

I claim:

The ornamental design for a wrist watch strap buckle as shown and described.

CHARLES B. GREENBERG.
